UNITED STATES PATENT OFFICE

139,154

DESIGN FOR A ROLLER TOY

Arthur Robb, Arlington, Va.

Application May 5, 1944, Serial No. 113,482

Term of patent 7 years

(Cl. D34—15)

To all whom it may concern:

Be it known that I, Arthur Robb, a citizen of the United States, residing at Arlington, in the county of Arlington and State of Virginia, have invented a new, original, and ornamental Design for Roller Toy, of which the following is a specification, reference being had to the accompanying drawing, forming part thereof, wherein:

Figure 1 is a perspective view of a roller toy, showing my new design;

Figure 2 is a top plan view thereof on a reduced scale; and

Figure 3 is a front view of Figure 2.

I claim:

The ornamental design for a roller toy, substantially as shown.

ARTHUR ROBB.
